Des. 236,029
Patented July 22, 1975

236,029

ACCESSORY MOUNT FOR A CAMERA OR SIMILAR ARTICLE

Edwin H. Land, Cambridge, and John B. Morse, Boston,
Mass., assignors to Polaroid Corporation

Filed Aug. 10, 1973, Ser. No. 387,233

Term of patent 14 years

Int. Cl. D16—05

U.S. Cl. D61—1 E

FIG. 1

FIG. 2

FIG. 3

FIG. 4

FIG. 5

FIG. 6

FIG. 1 is a left front perspective view of an accessory mount for a camera or similar article showing our new design;

FIG. 2 is a front elevational view thereof;

FIG. 3 is a rear elevational view thereof;

FIG. 4 is a right side elevational view thereof;

FIG. 5 is a top plan view thereof; and

FIG. 6 is a bottom plan view thereof.

We claim:

The ornamental design for an accessory mount for a camera or similar article, substantially as shown and described.
